UNITED STATES PATENT OFFICE.

HIRAM R. MALLINSON, OF NEW YORK, N. Y.

DESIGN FOR TEXTILE FABRIC.

46,176.

Specification for Design.

Patented July 28, 1914.

Application filed June 2, 1914. Serial No. 842,475. Term of patent 3½ years.

To all whom it may concern:

Be it known that I, HIRAM R. MALLINSON, a citizen of the United States, residing at New York city, in the county of New York and State of New York, have invented a new, original, and ornamental Design for a Textile Fabric, of which the following is a specification, reference being had to the accompanying drawing, forming part thereof.

The single figure of the drawing is a plan view of a portion of a textile fabric illustrating my new design.

I claim:

The ornamental design for a textile fabric as shown.

HIRAM R. MALLINSON.

Witnesses:

ROBT. BERRYMAN,
M. S. MEEM.
